Jesse Johnson.

UNITED STATES PATENT OFFICE.

JOSEE JOHNSON, OF NEW YORK, N. Y.

IMPROVED FRUIT-JAR.

Specification forming part of Letters Patent No. 56,226, dated July 10, 1866.

To all whom it may concern:

Be it known that I, JOSEE JOHNSON, of the city and county of New York, in the State of New York, have invented certain new and useful Improvements in Cans or Jars for Preserving Fruits, &c.; and I do hereby declare that the following is a full and exact description thereof.

My invention relates to the means of securing and releasing the cover.

I will first describe what I consider the best means of carrying out my invention, and will afterward designate the points which I believe to be new.

The accompanying drawings form a part of this specification.

Figure 1 is a side elevation of the upper part of the can with the cover loosely applied. Fig. 2 is a plan view of the same. Fig. 3 is a side view with the cover tightly secured. Fig. 4 is a corresponding plan view. Fig. 5 is a side view of a can-cover, showing a modification of the semi-spiral elevations on its upper surface, the semi-spirals being highest at their centers and slanting down both ways therefrom. Fig. 6 is a plan view of the same.

Similar letters of reference indicate like parts in all the figures.

A is the body of a jar, assumed to be of stoneware. A' is the neck, and a is a groove or recess extending uniformly around the neck. B b', &c., is the cover, and C C' is a semi-ring and strap formed in one piece, which serves as the means for confining the cover.

The cover is made to fit tightly upon the upper edge of the can or upon a surface near that level by means of a washer of rubber or by other approved means not represented. The cover is adapted to enter slightly into the mouth of the jar to guide it and prevent its moving laterally. Two semicircular inclined ridges or semi-spirals are formed on its upper face, as indicated by b' b².

The holding-piece C C' may be of malleable cast-iron japanned. The part C is half of a cylindrical ring. The part C' is a strap extending from one end of the ring upward and outward, thence horizontally across the top of the cover, and downward and inward to join the other end of the ring C.

The holding-piece C C' is made to tighten

or release the cover by partially turning the said holding-piece around the neck of the can.

It will be obvious that the semi-cylindrical ring will traverse around in either direction without leaving the groove, provided the strain is applied at the forward end so as to hold it firmly in the groove as it turns.

To operate my invention the can is filled and the cover is applied in the ordinary manner. The holding-piece is then taken in the fingers and applied in the position indicated in Figs. 1 and 2, in which position it can be dropped into its place. In this position of the parts the cross-piece C' rests on the beginning or lowest portions of the semi-spirals b' b². Now, by applying and maintaining a sufficient force at the point indicated by the arrow in Fig. 4, the confining-piece C C' will be turned around, the semi-ring C sliding around in the groove a, and the cross-piece C' traversing up on the semi-spirals b' b². This motion proceeds until the cross-piece C' presses with sufficient force upon the semi-spirals, so as to hold the cover tightly down. The can may now be left for an indefinite period, or may be transported, and no extraordinary care is necessary to avoid the displacement of the parts.

There being no strain on the center of the cover B, that portion of the cover may be made quite thin, and the entire cover may be made of glass, so as to allow the contents of the can to be plainly visible and so that their condition may be easily inspected.

To open the can it is easy to turn the confining-piece C C', either by hand or by any suitable wrench, and, on turning it back so that the cross-piece C' rests on the lowest parts of the spirals b' b², it will become loose and may be easily removed in the manner shown in Figs. 1 and 2.

A screw or other fastening may be introduced through my confining-piece, if desired, in order either to more firmly secure the confining-piece in its proper position upon the can or to increase the pressure upon the cover; but I have not found such to be necessary in my experiments.

The body and cover of my can may be both made of stoneware or of any approved material, or the body may be made of any one material and the cover of another.

The semi-spirals b' b^2 , instead of having their highest elevation at one end of the spiral, may be highest at their centers and slant down both ways therefrom. This form will allow the cover to be pressed down by turning the part C C' in either direction at pleasure.

If deemed necessary to prevent the part C' from slipping and the cover from being thus accidentally loosened, the upper surfaces of the semi-spirals may be slightly notched or waved for receiving the part C', as indicated in red outline, somewhat exaggerated, in Fig. 3.

Having now fully described my invention, what I claim as new, and desire to secure by Letters Patent, is as follows:

1. The semi-ring C and cross-strap C', arranged to operate relatively to the body and cover of a self-sealing can or jar, substantially as herein specified.

2. The partial spirals b' b^2 , arranged opposite to each other on the cover, in combination with a securing-piece, C C', substantially as and for the purpose herein set forth.

JOSEE JOHNSON.
